UNITED STATES PATENT OFFICE.

GEORGE M. D. BELL, OF LUCERNE, INDIANA.

DRIFT-WHEEL FOR PIERS AND BRIDGES.

1,077,508.

Specification of Letters Patent.

Patented Nov. 4, 1913.

Application filed May 22, 1913. Serial No. 769,148.

To all whom it may concern:

Be it known that I, GEORGE M. D. BELL, a citizen of the United States, residing at Lucerne, in the county of Cass and State of Indiana, have invented a new and useful Drift - Wheel for Piers and Bridges; and I do hereby declare the following to be a full, clear, and exact description of the invention, such as will enable others skilled in the art to which it appertains to make and use the same.

This invention relates to a new and useful improved drift wheel for piers and bridges.

15 An object of the invention is to provide a device of this nature for preventing drifts, rafts or logs or the like from stowing against bridges, piers, or docks or the like.

One of the features of the invention is 20 the provision of a heavy solid metal wheel, the periphery of which is armored with spikes, and yieldably mounted with relation to the bridge, pier or the like, in front or under the same, so that when the drifts or 25 floating logs pass, they rotate the wheel, and slide or drift along. The yieldability of the wheel relieves or absorbs the sudden impact or jar upon the bridge, pier or the like. If the wheel be arranged in a horizontal 30 plane from the bridge or the like, the yieldability is not only in the direction of the bridge, but also vertically, and if the wheel is mounted under the bridge, the yieldability is likewise in two directions.

35 If desired, the bridge, pier or the like may be equipped with a plurality of said wheels, as shown in the drawings, so as to maintain the various objects fully under the water, so as to slide along.

40 In practical fields the details of construction may necessitate alterations, to which the patentee is entitled, provided the alterations fall within the scope of what is claimed.

45 The invention comprises further features and combinations of parts, as hereinafter set forth, shown in the drawings and claimed.

In the drawings:—Figure 1 is a view 50 showing the application of several of these armored wheels, as attached to a bridge or the like, so as to keep the drifts well on their way under the bridge or past the pier. Fig. 2 is a view showing only one of said 55 wheels. Fig. 3 is an enlarged detail view.

Fig. 4 is a view showing the yielding springs eliminated.

Referring more especially to the drawings, 1 designates a portion of a bridge, pier or the like, to which a plurality of brackets 2 are secured by means of heavy stout steel spring straps 3, which yield incident to drifts, rafts or logs coming in contact with the heavy solid wheels 4. These wheels are provided on their periphery with spikes or pointed lugs 5, so that the drifts, logs or other objects will not slip relative to the wheel. Said wheels are arranged in the bifurcations 6 of the brackets, and their stub shafts 7 are mounted in the slots 8 of the arms 10 of the brackets, there being springs 11 arranged in the slots 8, against which the shafts act. In other words, when an object comes in contact with the wheel, the springs 11 yield incident to the impact. The springs 11 of the brackets of the side of the bridge yield in the direction of the bridge, while the steel spring straps 3 allow the wheel to yield upwardly. The springs of the brackets under the bridge yield vertically incident to the impact, while the springs 3 allow the brackets to yield laterally.

In Fig. 4 the springs 11 are dispensed with, nevertheless the bracket is allowed to yield upwardly.

On narrow bridges or piers it may be only necessary to utilize one, or possibly two of said drift wheels, but in extremely broad bridges or the like, it may be necessary to utilize a number of said drift wheels, it being the privilege of the inventor to utilize as many drift wheels as desired.

The invention having been set forth, what is claimed as new and useful is:—

1. In combination with a pier, a bracket having a bifurcation, a heavy steel spring strap for securing the bracket yieldably to the pier, and a heavy solid metal wheel mounted in said bifurcation and having its periphery armored with spikes.

2. In combination, a heavy solid metal drift wheel having its periphery armored with spikes, a bracket member having a bifurcation and provided with arms, a stub shaft mounted in said arms, and on which shaft the wheel is mounted, said wheel extending into said bifurcation, and a heavy steel spring strap for securing the bracket member yieldably to a pier.

3. In combination, a heavy solid metal drift wheel having its periphery armored with spikes, a bracket member having a bifurcation and provided with arms, a stub shaft mounted in said arms, and on which shaft the wheel is mounted, said wheel extending into said bifurcation, said arms having slots, springs in said slots against which the stub shafts act, and heavy steel spring

straps for securing the bracket member 10 yieldably to a pier.

In testimony whereof I have signed my name to this specification in the presence of two subscribing witnesses.

GEORGE M. D. BELL.
